INVENTOR:

Henry Draper

United States Patent Office.

HENRY S. DRAPER, OF ROCHESTER, NEW YORK, ASSIGNOR TO HIMSELF AND JOHN A. JORDON, OF SAME PLACE.

Letters Patent No. 91,726, dated June 22, 1869.

IMPROVEMENT IN FRUIT-JARS.

The Schedule referred to in these Letters Patent and making part of the same.

To all whom it may concern:

Be it known that I, HENRY S. DRAPER, of Rochester, in the county of Monroe, and State of New York, have invented a new and useful Improved Fruit-Jar; and I do hereby declare that the following is a full, clear, and exact description thereof, reference being had to the accompanying drawing, making part of this specification, in which—

Figure 1 is a vertical section.

Figure 2 is a side elevation, with part of the rubber ring broken away to show the vent-hole.

My invention relates to "fruit-jars," and consists in a novel construction of the neck and cover of the jar, so that they may be held securely together by a rubber band, which serves, at the same time, to close a vent in the cover, and is so arranged that it can be conveniently removed therefrom when desired.

In the drawings—

Fig. 1 is a vertical section, and

Fig. 2 is a side view, showing a portion of the rubber band broken away.

In constructing my fruit-jar A, I provide its neck with a shoulder, *b*, and a flange, *f*, and its cover with a vent-hole, *e*, and flange *e*, and shoulder *a*, as clearly shown in fig. 1, and so constructed that the shoulder of the cover shall fit over the shoulder of the neck, as shown in the same figure.

The portion of the cover B below the flange *e*, and the portion of the neck of the body A above the flange *f*, I so construct, that when the cover B shall be in

place, as unitedly to form a uniform convex surface between the flanges *e* and *f*, as is also shown in fig. 1, and then, about this convex surface I place the rubber band *d*, as shown in both figures.

The flanges *e* and *f*, on the cover and the neck, serve to prevent the band from slipping, and their curved surfaces cause the band to bind or hold the cover securely in place.

Immediately above and in line with the vent *e*, I make a depression, *g*, in the flange *e*, as clearly shown in fig. 2, for convenience in opening the jar.

When the jar is filled and closed, the rubber band, in passing over and shutting the vent, at the same time conceals it, and without something to indicate its position, it would require a little time to discover it; but by my arrangement its locality is shown, and the thumb or finger can be conveniently applied or passed down the depression, against the rubber band, removing it from the vent, and thus the cover released and the jar opened.

Having thus described my invention,

What I claim, is—

A fruit-jar, having its neck and cover so constructed as to be held together by a rubber band, and having its cover provided with a vent, *e*, and depression *g*, all as herein shown and described.

HENRY S. DRAPER.
